FISH LURE

Leon Bradberry, 2504 College Ave., Berkeley, Calif.

Filed Mar. 27, 1961, Ser. No. 64,498

Term of patent 14 years

(Cl. D31—4)

The dominant features of my design reside in the portions shown in full lines.

I claim:

The ornamental design for a fish lure, substantially as shown and described.
